UNITED STATES PATENT OFFICE.

BEN HIRSCH, OF NEW YORK, N. Y.

ALBUM FOR PHONOGRAPH RECORD-DISKS.

No. 909,410.

Specification of Letters Patent.

Patented Jan. 12, 1909.

Application filed January 28, 1908. Serial No. 413,134.

To all whom it may concern:

Be it known that I, BEN HIRSCH, citizen of the United States, residing at New York, in the county of New York and State of 5 New York, have invented certain new and useful Improvements in Albums for Phonograph Record-Disks, of which the following is a specification.

To those familiar with the use of phonographs of that type that employ disk records, it is well known that the handling and disposition of the records, when not in use, are a matter of considerable concern, as the repeated handling of the records in hunting 10 for a desired selection, tends to scratch same and renders them liable to become broken, and the indiscriminate piling of the records one upon the other or in boxes, also tends to scratch them and renders somewhat difficult 15 the finding of any particular record, also resulting in dust settling in the grooves and affecting the sound of the record.

With this knowledge in view, and to overcome the difficulties above mentioned, as well 20 as others that will at once occur to the users of phonographs of this type, my invention has for its object a simple and efficient construction of album designed particularly for holding and preserving phonograph record 25 disks, and I shall now describe the invention, setting forth the details of construction and arrangement of the parts, and then point out the novel features in the appended 30 claim.

For a full understanding of the invention, reference is to be had to the following description and accompanying drawing, in which:

Figure 1 is a perspective view of an album 40 embodying the improvements of my invention, the same being shown partly opened in order to better illustrate the construction. Fig. 2 is a horizontal sectional view through several of the album leaves, on a larger scale.

Fig. 3 is a vertical sectional view of one leaf.

Corresponding and like parts are referred to in the following description and indicated in all the views of the drawings by the same reference characters.

The backing 1 of my improved phonograph disk album may be of any desired size, construction and design, according as judgment or taste may dictate, and between the two parts of said backing and secured 55 thereto at one edge in any desired way will

known in the book binders' art, are any desired number of leaves 3. These leaves are so arranged as to provide compartments for the record disks, and each one contains two compartments, so as to economize space as well as to show or display the title of the records through each and every page of the album. For instance, as best seen in Figs. 2 and 3, each leaf comprises one or two plies of suitably heavy or stiff card-board 4 laid one against the other and relatively thin or flexible, and yet sufficiently tough or strong, paper sheets 5 that are applied to opposite sides of the partition formed by the card-board, the ends of the paper 5 being turned inwardly between the two plies, as indicated at 6, and the whole being pasted together so as to secure the two plies together throughout their extent and the two inwardly turned edges of the paper between 70 the ends of the plies. It will thus be seen that each leaf embodies a middle partition formed by the part or parts 4, and two compartments on opposite sides of said partition, each compartment being designed to contain a record disk slipped therein through one end. The paper forming the outer side wall of each compartment is formed with a sight opening 7 of a size to encompass the central portion of the disk upon which the name of the composition reproduced thereby is imprinted or otherwise displayed. It will thus be understood that the names of the compositions on the respective disks may be easily ascertained without removing any of 80 the disks from the album, by simply turning over the leaves until the desired disk comes to light. Then said disk may be easily withdrawn from the album by grasping it through the recesses 8 formed in the upper 90 edge of the outer wall of the compartment in which it is stowed. Obviously, the albums may be indexed and the pages numbered so that one may turn at once to the composition desired, and the back of the album may 95 also be characterized in any desired way, so as to distinguish one album from the others in a set.

From the foregoing description in connection with the accompanying drawing, it 100 will be seen that I have provided a very simple and efficient means for holding a plurality of record disks for phonographs where they will not be exposed to dust and by the means of which any selection may 110

be secured without touching any of the disks or otherwise handling them except to turn the pages of the album, this operation, obviously, not injuring the disks in any way. 5 As a matter of fact, the album provides an additional means of security for the disks in that they are not so liable to be broken as when they are permitted to lie around loose, and I have found by experience that the 10 album may be dropped and otherwise roughly handled without liability of injury to the disks, due in a measure to the protection of the backing 1 and the separation of one disk from the other by the card-board 15 partitions and paper portions of the leaves. It is evident that any desired form of clasp may be secured across the upper end of the album so as to hold the leaves together, as well as prevent the accidental 20 placement of the disks therefrom.

Having thus described the invention, what is claimed as new is:

As a new article of manufacture, an album for record disks of phonographs, embodying a plurality of leaves each of which comprises two plies of pasteboard laid face to face and paper sheets having their ends in-turned between the two plies, said paper sheets being applied on the opposite face of the unit formed by the two plies, the plies 25 being pasted together throughout their extent so as to secure the inwardly turned edges of the paper between the ends of the plies. 30

In testimony whereof I affix my signature 35 in presence of two witnesses.

BEN HIRSCH. [L. s.]
